UNITED STATES PATENT OFFICE.

GEORGE R. RICH, OF BUCHANAN, MICHIGAN, ASSIGNOR TO CELFOR TOOL COMPANY, A CORPORATION OF ILLINOIS.

MULTIPLE DRILLING-MACHINE.

No. 925,508.

Specification of Letters Patent. Patented June 22, 1909.

Application filed July 24, 1905. Serial No. 271,095.

To all whom it may concern:

Be it known that I, GEORGE R. RICH, a citizen of the United States, residing at Buchanan, in the county of Berrien and State of Michigan, have invented certain new and useful Improvements in Multiple Drilling-Machines, of which the following is a specification, reference being had to the accompanying drawings.

10 My invention relates to multiple drilling-machines, and it has particularly for its object to provide a new and improved machine suitable for use in drilling holes simultaneously in different parts of arch-bars for car-trucks, or similar articles, although many features thereof may be embodied in various other forms of drilling-machines besides that illustrated in the drawings and hereinafter described. In the accompanying drawings I

15 have illustrated various features of my invention embodied in an arch-bar drill-press arranged and operating to drill simultaneously two holes at opposite sides of the center of the arch and also two holes in the end portions of the arch-bar. Each hole is drilled by a drill mounted in a separate spindle or chuck,—the different spindles being so supported as to be independently adjustable toward and from each other, as well as toward

20 and from the work, but all the drills are driven simultaneously from a common source of power,—all being connected with the same drive-shaft. The work is carried on a vertically-movable table provided with hand-operated mechanism for moving it rapidly

25 toward and from the drills, and with automatic power-driven mechanism for feeding the work toward the drills during the actual operation of drilling. The latter is automatically thrown out of operation upon the completion of the drilling operation. The mechanism for controlling the feed is placed in front of the feed-table so as to be readily accessible to the operator. The driving-

30 mechanism also actuates a pump arranged to throw water upon the drills during the drilling operation,—the water flowing from the drills back to the pump, so that the same water is used repeatedly. In the drill-press

35 illustrated I have also shown a number of other improvements relating to the construction and operation of the machine,—all of which are fully hereinafter described and pointed out.

What I regard as patentably new is set forth in the claims.

In the drawings.—Figure 1 is a front view of my improved drill-press; Fig. 2 is an end elevation thereof; Fig. 3 is a vertical section on line 3—3 of Fig. 1; Fig. 4 is a plan view; Fig. 5 is a horizontal section on line 5—5 of Fig. 1; Fig. 6 is a horizontal section on line 6—6 of Fig. 1; Fig. 7 is an enlarged cross section on line 7—7 of Fig. 6; Fig. 8 is an enlarged partial vertical section through the upper portion of the frame and some of the parts carried thereby, as, for example, on line 8—8 of Fig. 4; Fig. 9 is a partial horizontal section on line 9—9 of Fig. 1; Fig. 10 is an enlarged partial vertical section on line 10—10 of Fig. 1; Fig. 11 is a partial horizontal section on line 11—11 of Fig. 10; Fig. 12 is an enlarged vertical section on line 12—12 of Fig. 1; Fig. 13 is a perspective view, illustrating a part of the upper portion of the frame; and Fig. 14 is a partial sectional view on line 14—14 of Fig. 3.

Referring to the drawings,—20 indicates the base of the press, which is of suitable shape and so constructed as to support the necessary parts. As shown in Figs. 4 and 5, the base is oblong, being, in the apparatus illustrated, about four times as long as it is wide. These proportions may, of course, be varied as may be desired.

21—22 indicate uprights or standards rigidly secured to the base near the ends thereof, as best shown in Figs. 1, 4 and 5. Said standards not only serve in part as guides for the feed-table, but also support various other parts of the mechanism, as will be herein-after described.

23 indicates a well or basin placed near one end of the base, preferably the left-hand end, as shown in Fig. 5, to receive the water falling upon the upper surface of the base,—the said upper surface being properly pitched to that end, as shown at 24 in Fig. 3.

The front edge 25 of the base projects upward beyond the intermediate portion of the surface of the base, as shown in Fig. 3, so as to prevent overflow.

26 indicates a pump connected by a pipe 27 with the basin 23 for pumping water therefrom and forcing it to the drills, as herein-after described.

28 indicates a plate or frame arranged at the back of the press and extending between

the standards 21—22, to which its ends are fixedly secured. For convenience, said plate will be termed the "back-plate". Said plate, together with the standards and base, 5 may be said to compose the frame of the machine; but it will be understood that the frame may be otherwise made up,—it being essential only that it be of proper strength and proportions to support the working parts 10 of the machine.

29 indicates a groove which extends longitudinally of the back-plate 28 at or near its upper margin, as shown in Figs. 1 and 13,—said groove being formed by upwardly 15 and downwardly projecting flanges 30—31, respectively, as shown in Fig. 13. The object of said groove is to secure and guide the upper portions of the different spindle-supporting frames. 32—33 indicate similar 20 grooves at the end portions of the back-plate 28 near the lower margin thereof; and 34 indicates a similar groove intermediately disposed near the lower margin of said back-plate, as shown in Fig. 1. The grooves 32, 25 33 and 34 are to support and guide the lower portions of the different spindle-supporting frames.

A, B, C, D, E, F indicate a series of drilling-devices, which are all alike and are similarly 30 mounted on the back-plate 28. They are also similarly driven, so that it will be necessary to describe in detail the construction and connections of a single one only,—it being understood that the same reference numbers 35 are applied to corresponding parts of each of said drilling-devices. As best shown in Fig. 1, there are a series of spindle-supporting frames 35 vertically disposed upon the front side of the back-plate 28,—said 40 frames being secured thereto at their upper ends by bolts 36 having heads 37 which fit in the groove 29, as best shown in Fig. 8. Similar bolts are provided for engaging the grooves 32, 33 and 34 to secure the lower end 45 portions of the frames 35 in position. Obviously, by loosening the nuts 38, the frames 35 may be shifted longitudinally upon the back-plate 28 and brought to the desired position. As also shown in Fig. 8, the frames 50 35 are provided at their upper ends with flanges 39, which extend over the upper edge of the back-plate 28 and further support said frames.

40 indicates the housings or cylinders of 55 the different spindles, each of which, as best shown in Fig. 9, is provided at the back with a slide-plate 41 adapted to fit against and slide vertically upon the frame 35. The slide-plates 41 are held in position by overlapping guide-strips 42 secured longitudinally 60 on the frame 35 at opposite margins thereof, as shown in Figs. 1, 8 and 9. Bolts 43 are provided for securing the strips 42 in position. The arrangement is such that said 65 strips may be caused to bind tightly upon the

slide-plate 41 by tightening the bolts 43, thereby clamping the slide-plate and spindle cylinder fixedly in position. By this means the spindle may readily be moved vertically and secured in different positions of adjustment, and the operative height of the drill carried thereby varied. Each cylinder 40 is provided with a forwardly-projecting handle 44 by which it may be more readily moved.

45 indicates the spindles, which carry 75 drills 46 projecting beyond the lower ends of the cylinders 40, as shown in Fig. 1. The spindles 45 may be provided with any suitable mechanism for securing the drills in position and causing them to rotate, but I preferably employ the construction illustrated and described in my pending application, Serial Number 265,679, filed June 17, 1905; and the drill is preferably also of the type described in my said application, being of 80 blue-chip steel of uniform cross section throughout its length and being provided with longitudinal ribs extending along its opposite sides, as indicated in the drawings. The spindle is connected with driving-mechanism, hereinafter described, by means of a sleeve 47 which may be an integral part of the spindle and fits upon a vertical shaft 48 having a feather 49, as shown in Fig. 2, so that said sleeve may move longitudinally 85 thereof and nevertheless rotates in unison therewith.

50 indicates a sleeve secured at the upper portion of the frame 35 and forming a bearing for the upper end of the shaft 48. The lower end of the shaft 48 is held properly in 90 position by the sleeve 47 and spindle cylinder 40.

The shaft 48 is driven by means of a beveled-gear 51 mounted on its upper end and meshing with a beveled-gear 52 mounted on a feathered-shaft 53, the ends of which are journaled in the standards 21—22, as shown in Fig. 1. The gear 52 is feathered on the shaft 53 so that it may be adjusted to different positions thereupon. At one end the shaft 53 carries a gear 54 which meshes with a pinion 55 mounted on a shaft 56, best shown in Fig. 2, which carries a cone-pulley 57. By this means the shaft 53 may be 100 driven at various speeds. At the opposite end the shaft 53 carries a beveled-pinion 58, as best shown in Fig. 1, through which it is operated, as will be hereinafter described.

The spindle-cylinder 40 and spindle are 105 counterbalanced by a counterbalance-weight 59 carried by a chain 60 which runs over a pulley 61 and is connected by a hook 62, or other suitable means, with the cylinder 40, as shown in Fig. 3. The pulley 61 is carried 110 in a frame 63, which projects from the upper portion of the frame 35, as shown in Fig. 3. The pulley 61 may, however, be carried in any other suitable way so as to move with the frame 35 when the latter is adjusted. In 115 120 125 130

order to cause the gear 52 to move with the frame 35, when the latter is adjusted, said gear is provided with a sleeve 64 having an annular flange 65 at its outer end, as shown in Fig. 14; and the frame 63 is arranged to embrace said sleeve; as is also shown in Fig. 14. Consequently, when any one of the frames 35 is adjusted longitudinally of the machine the gear 52 and the counterbalancing-mechanism move with it.

66 indicates the feed-table, which, as shown in Fig. 1, extends longitudinally of the machine near the lower portion thereof, its ends being fitted between suitable guides 15 67—68—69—70 carried by the standards 21—22; as shown in Fig. 6. The feed-table is arranged directly under the drill points, which overlie the longitudinal central line of the feed-table, and said table is arranged 20 to be moved vertically to carry the work toward or from the drills. Said table is mounted near its ends upon screws 71, which are fitted in suitable tubular supports 72 secured upon the base 20, as best shown in Fig. 12. 25 The supports 72 are provided with intermediate screw-threaded portions to receive the threads of the screws 71, and at their lower ends are provided with oil-cups 73, into which the lower ends of the screws project. 30 At their upper ends the screws 71 are provided with beveled gears 74, the under surfaces of which are provided with annular bearings 75 which rest on antifriction-balls 76 carried at the upper ends of the supports 35 72. The gears 74 are connected by a shaft 77, which is fitted in suitable bearing-blocks 78—79 near the ends of the feed-table and carries beveled gears 80 meshing with the beveled gears 74, as shown in Fig. 6. Obviously by rotating the shaft 77, both gears 77 and screws 71 are rotated. The arrangement is such that both screws are similarly operated,—that is to say, both rise or descend simultaneously. If desired, one of 40 the screws 71 may be made right hand and the other left hand so that they may be rotated in opposite directions simultaneously,—in which case the gears 80 are arranged as shown in Fig. 6; or the gears may 45 be arranged to rotate the screws in the same direction,—in which case similar screws would be employed.

81 indicates a beveled-gear mounted on the shaft 77 and meshing with a beveled-gear 55 82 mounted on a stub-shaft 83 which projects from the front of the feed-table, as shown in Fig. 6, and carries a hand-wheel 84 by which it may be rotated. By this means the shaft 77 may be rotated by hand to raise or lower 50 the feed-table. In order to operate the feed-table by power I provide the shaft 77 with a pinion 85, which is adapted to mesh with a pinion 86 mounted upon a shaft 87 which projects through one end of the feed-table 60 65 and through a slot in the standard 22, as

shown in Fig. 6. The inner end of the shaft 87 is fitted in a suitable bearing 88 provided in one arm 89 of a bell-crank lever 89^a,—the other arm 90 of which projects through an opening 91 in front of the feed-table, as shown in Figs. 6 and 7. As shown in Fig. 7, said lever is pivoted in a suitable bracket 92, so that by lifting the arm 90 the shaft 87 and pinion 86 are thrown over toward the pinion 85. By this means the pinion 86 may be 70 moved into or out of engagement with the pinion 85 by operating the arm 90 of the bell-crank lever. In practice, the arm 90 is raised by hand, but it is held in its raised position by a latch 93 having an upright arm 80 94 and a horizontal arm 95, as shown in Fig. 1. The arm 94 of said latch is provided with a lug 96 adapted to project under the arm 90 to hold it in its raised position. The arm 95 of said latch projects over an arm 97 of a trip-lever 98, the opposite arm 99 of which is adapted to engage an adjustable stop 100 carried by the standard 24. The stop 100 may be secured in different positions of adjustment by a bolt 101, as shown in Fig. 1. 90 The arrangement is such that when the arm 99 of the trip-lever strikes the stop 100 the arm 97 of said trip-lever is thrown upward, thereby lifting the arm 95 of the latch 93 and throwing the arm 94 away from the arm 90 95 of the bell-crank lever which is released and permitted to drop, thereby throwing the pinion 86 out of engagement with the pinion 85. The result is that the shaft 87 is automatically disconnected from the shaft 77, stopping the feed-table. This, however, does not interfere with the movement of the feed-table by means of the hand-wheel 84, as will be apparent.

The shaft 87 is driven from the shaft 53 by 105 means of a vertical shaft 102, which, at its upper end, is provided with a beveled-pinion 103 meshing with the pinion 58, and at its lower end carries a pinion 104 which meshes with a pinion 105 carried by the shaft 87. 110 The pinion 104 is mounted on a feather 106 on the shaft 102, so that it may be moved longitudinally thereof, and it is held in engagement with the pinion 105 by a yoke 107, as shown in Fig. 1. The shaft 87 is, therefore, constantly rotated, but it does not drive the shaft 77 except when the pinions 85 and 86 are in mesh. It will be noted that the parts are so arranged that when driven by power the hand-mechanism for moving the 120 feed-table is geared considerably higher than the power mechanism,—as it is desirable that the feed-table may be moved faster when moved by hand than when driven by power.

The feed-table also is provided with suitable counterbalancing - weights 108 placed near its opposite ends and connected by chains 109 with pulleys 110 mounted in the standards 21—22, respectively, as shown in 130

Fig. 10. In order to give the said weights greater leverage, and thereby make it practicable to use smaller weights, the ends of the feed-table are connected with the pulleys 110 by means of chains 111 which connect with pulleys 112 of considerably less diameter than the pulleys 110, but mounted on the same shafts 113, which carry said pulleys 110, as shown in Figs. 10 and 11. The lower 10 ends of the chains 111 are connected in any suitable way with the ends of the feed-table. 114 indicates idler-pulleys for guiding the chains 111.

115—116 indicate clamps carried by the 15 feed-table near the ends thereof for clamping the ends of the work thereto, as shown in Figs. 1 and 5. Said clamps are provided with cams 117 by which the work is clamped tightly against lugs 118, as shown in Fig. 5.

20 At its center the feed-table 66 carries a vertically-adjustable central clamp and work-support 119, which is mounted on a screw-threaded stem or standard 120, as shown in Figs. 1 and 3. The stem 120 carries a nut 25 121 by adjusting which the height of the clamp 119 may be varied. Said clamp also carries cams 122 by which the work may be clamped against a lug 123, as shown in Fig. 3.

124 indicates a vertically-disposed guide-30 plate, which is formed integral with the rear portion of the center-support 119 and extends above and below the same, as shown in Fig. 3. The upper end of said guide-plate bears against the rear surface of the back-35 plate 28, and its lower end bears against the rear face of the feed-table 66, as shown in said Fig. 3. Said guide-plate therefore not only serves to keep the center-support 119 steady, but also steadies and guides the feed-table 40 and insures the movement of the work in a vertical plane.

125 (see Figs. 1, 2 and 5) indicates a pipe leading from the pump 26 to the upper portion of the machine and arranged to dis-45 charge water upon the different drills for cooling purposes. The pump 26 is operated from a pulley 126 on the shaft 56 by a belt 127 indicated by dotted lines in Fig. 1.

The operation is as follows:—The several 50 spindles are set at the proper distances apart, and at the proper heights. For drilling arch-bars they are set as illustrated in Fig. 1. The center support 119 is also elevated correspondingly. When in proper position the 55 different spindle-cylinders 40 are secured fixedly in position by tightening the bolts 43. The arch-bar is then put in position and secured by the clamping-devices 115, 116 and 119. At this time the feed-table is in its 60 lowermost position. The stop 100 is set at the proper height to trip the automatic feed-mechanism upon the completion of the boring operation. All being in readiness, the hand-wheel 84 is then rotated to elevate the

feed-table rapidly until the arch-bar is in proximity to the drills. The arm 90 of the bell-crank lever 89^a is then lifted into engagement with the lug 96, thereby throwing the automatic or power-feeding mechanism into operation. The arch - bar is thereby fed 70 slowly up against the drills until the drilling operation is completed, when the lever 98 is actuated by the stop 100 to trip the arm 90 and throw the automatic feed out of operation. It will be understood that when the 75 arm 90 of the bell-crank lever 89^a is released the weight of said arm 90 suffices to throw the shaft 87 far enough away from the shaft 77 to disengage the pinions 85—86. The feed-table comes to a stop as soon as said pinions are disengaged and may be returned to its former position by reversely rotating the hand-wheel 84. It will be noted that all the 80 holes are drilled simultaneously, and as each of the drills is fixedly secured in its proper 85 position the different holes are drilled with the utmost accuracy.

It is apparent that any desired number of spindles may be employed, and they may be disposed so as to drill holes at any desired intervals, or at a variety of heights above the feed-table, so that the machine has a wide range of usefulness; particularly so, in view of the fact that the various adjustments of which the drills are capable may be quickly 90 and accurately made without the exercise of 95 any considerable amount of skill.

While I have described my improved drill-press with a considerable degree of particularity, I wish it to be understood that in doing 100 so I have not intended to restrict myself to the specific features of construction illustrated and described, except in so far as they are particularly claimed,—it being my intention to claim generically the subject-matter 105 of the broader claims.

While the spindles shown are illustrated and described as being intended for use in holding drills, spindles for holding other tools may be used in the same way, and the 110 term "drill" as used in the claims is used in a generic sense to comprehend any drill or other tool used in a spindle, or equivalent holder.

That which I claim as my invention and 115 desire to secure by Letters Patent is,—

1. A machine-tool, comprising a machine-frame, a spindle carried thereby, a vertically-movable feed-table, end-guides for said feed-table, carried by said frame, and an intermediate guide carried by said feed-table and bearing against the back of said machine-frame. 120

2. A machine-tool, comprising a machine-frame, a vertically-movable feed-table, end-guides for said feed-table, a vertically-adjustable work-supporting clamp carried by said feed-table, and a rigid guide-plate con- 125

nected with said clamp and bearing against said feed-table and the back of the machine-frame.

3. A machine-tool, comprising a machine-frame, a vertically-movable feed-table, end-guides for said feed-table, a vertically-adjustable work-supporting clamp carried by said feed-table, and a guide-plate connected with said clamp and extending above and below the same, the upper portion of said guide-plate bearing against the back of the machine-frame and the lower end portion thereof bearing against the feed-table.
- 10 4. A machine-tool, comprising a machine-

frame, a feed-table, a work-support mounted 15 on said feed-table and adjustable vertically independently thereof, and a guide connected with said work-support, said guide projecting above and below said work-support, the upper end of said guide having a bearing 20 against the machine-frame and the lower end thereof having a bearing against said feed-table.

GEORGE R. RICH.
